(57) **CLAIM**

I claim the ornamental design for a steering wheel lock, as shown and described.

DESCRIPTION

FIG. 1 is a perspective view of a steering wheel lock showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an embodiment showing the steering wheel lock in use.

The broken lines in FIG. 8 are for the purpose of illustrating the environment of the design and form no part of the claimed design.
